FranceApplication October 25, 1934, Serial No. 749,989
In France October 25, 1933

3 Claims. (Cl. 70—293)

The present invention relates to a puzzle mechanism and more particularly to a keyless lock.

The object of the invention is to provide a device so constructed that searching of the key numbers, for opening the lock, is practically rendered impossible unless the operator knows the combination.

Other objects of the invention will be apparent in the description to follow.

10 As an example and for purposes of illustration a drawing is attached herewith wherein:

Figure 1 shows a bottom view of the apparatus with the bottom plate removed,

Figure 2 is a vertical section of Figure 1,

15 Figure 3 shows the bottom plate assembled on the device,

Figure 4 illustrates a stop washer,

Figure 5 is an axial section of Figure 4,

15 Figure 6 represents a partly toothed pinion 20 used in the lock, and

Figure 7 depicts an abutment.

Referring to the drawing, wherein similar reference numerals represent corresponding parts throughout, 1 shows the casing of the lock to the centre of which is mounted a pinion 2 having an offset central disc portion forming a bearing for supporting the pinion rotatably in the casing wall, as shown in Figure 2. The pinion 2 is provided with a number of small teeth and 25 larger teeth 3, equally disposed around the periphery of said pinion. Equally spaced projecting pins 4 are also fixed near the peripheral edge of the pinion adjacent the large teeth 3 already described.

30 A number of small pinions 8 are rotatably mounted on the casing, said pinion being movable by means of knobs 14 extending outside of the casing and which knobs are adapted also to move segmental pinions 9 having a certain number of teeth co-acting with the small teeth of pinion 2, a notch 10 adapted to mesh with the large teeth of pinion 2 and a number of small 35 depressions 23. Also mounted together with the pinions 8 and 9 and rotatable by the knobs 14 are a number of washers 12 having an outward stop 12' adapted to abut against the pins 4 and a projecting pin 22 provided to enter the corresponding depressions of the contacting pinions 9.

40 Pawls 5 secured to the casing and having a blocking nose 6 are mounted to contact with the pins 4 of the central pinion 2, said pawls being spring pressed against the pinions 8. A stationarily fixed abutment 7 is adapted to contact with the large teeth of the central pinion, so as to 45 limit the clockwise movement of pinion 2. The

device is completed by a square spindle 13 secured to the central pinion 2 and adapted to be rotated by means of a driving handle extending to the back of the apparatus. A screw 11 is used to secure to the knobs 14, as previously disclosed, 5 the pinions 8, 9 and washer 12, so as to permit rotation thereof together with the knobs.

In order to drive the mechanism of the lock a groove 16 is provided in the offset central section of pinion 2 for insertion of a screw driver, 10 coin or the like. The mechanism is closed by bottom plate 17 secured to the casing by means of screws 20 entering threaded apertures 21 disposed in the casing. A dial 18 is provided on the bottom plate, surrounding the screws 11, a 15 groove 19 in the pinion 8 enabling the accurate rotation of pinions 8 with respect to the lines of the dial, said dial permitting changing the combination number.

In operation the device works as follows:

20 When in the position shown at Figure 1, the pinion 2 obviously can be rotated anti-clockwise so that its large teeth 3 enter the notches 10 of the pinions 9 which are correspondingly driven. Assuming that the pinions 9 are not in the "open" 25 position shown in Figure 1, that is, with the notch 10 directly facing the central pinion 2, the said pinions must be first brought into said position by means of the knobs 14. The stops 12' of the washer 12 co-operate with the projecting 30 pins 4 to provide a starting point from which the pinion is to be turned, said turning being effectuated by counting the clicks corresponding with the successive numerals counted by the operator to bring the pinions 9 in meshing position 35 with regard to the pinion 2. Consequently, the discovery of the combination number by any unauthorized person is rendered difficult since the spring actuated pawls 5 engaging the pinions give the impression of a continuously toothed 40 pinion, whereas the main pinions 9 are deprived of teeth over a certain portion of their periphery. When the large teeth of the pinion 2 come adjacent the pinion 9, the rotation of the pinion 8 pushes the nose 6 of the pawl 5 towards the 45 centre of the apparatus whereby the said nose 6 contacts with pin 4 to prevent the pinion 2 from turning. The pawls 5 do not gag when the pinions are correctly set; to accomplish this purpose, the pinion 2 is deprived of teeth at certain parts of its circumference. Thus, in the position shown in Figure 1, the pinions do not mesh and, therefore, pinion 2 may be turned somewhat without moving the pinion 9. Whenever the large 50 teeth of pinion 2 enter the notches 10, the pins 55

4 have passed before the nose of the pawls 5 and said pawls pushed forward by the teeth of pinion 8 no longer contact with pin 4 so that blocking is prevented.

5 The bottom of the apparatus being provided with dials, as shown at Figure 2, the "open" number may easily be changed after unscrewing slightly the screws 11 in order to revolve the knobs 14 to the right till the grooves 19 face 10 the required numerals. The screws 11 are therefore tightened to clamp together the pinions 8-9 and the washers 12 secured to the knobs 14. The number of numerals is optional but must necessarily correspond with the number of teeth 15 in pinion 8.

It is to be understood that the forms of my invention herein shown and described is to be taken as a preferred example of the same, and that various changes as to the shape, size and arrangement of parts may be resorted to without departing from the spirit of the invention or the scope of the subjoined claims.

1. In a keyless lock, in combination, a casing, a central member adapted to actuate a suitable member for locking purposes, a central pinion secured in the casing and having a number of small teeth, a plurality of large teeth and projecting members fixed to said pinion, a stationarily fixed abutment for said large teeth, rotatable controlling means comprising a knob for every large tooth of said central pinion, small pinions having a radial mark for purposes of reference, segmental pinions having a notch adapted to receive the large tooth of said central pinion and a number of depressions, a washer contacting said segmental pinions and having a projection adapted to enter the depressions of said segmental pinion and an outward stop adapted to abut against the projecting members 30 of said central pinion, a number of pawls adapted to prevent rotation of the small pinions and which sets between the teeth of the small pinion and the projections whenever it is tried to open

the lock before the correct formation of the combination member.

2. In a keyless combination lock having a suitable locking member, a casing, a main pinion centrally journaled in said casing and adapted to be manipulated from the outside to actuate the locking member, means to limit the movement of said pinion in one direction, a plurality of segmental pinion assemblies adapted, in a certain position, to mesh with the main pinion 10 and be driven thereby, spring-pressed pawls associated with the said assemblies for locking the main pinion whenever the assemblies are not in correct meshing positions, knobs for exteriorly actuating the assemblies, and means for selectively changing the relative position of the assemblies with respect to the main pinion so as to change the combination.

3. A keyless lock, comprising a casing, a pinion centrally mounted in said casing and having means actuating a suitable locking member, said means being accessible from outside the casing, a number of small and large teeth formed in the pinion at regular intervals therearound, the pinion further having non-toothed portions adjacent the large teeth, a projecting pin secured to the pinion at each non-toothed portion thereof, segmental pinions having small teeth corresponding with those of the central pinion as well as a notch for receiving the large teeth thereof for engagement thereby, pinions movably held to the segmental pinions, spring pressed pawls resting on the pinions teeth and adapted to cooperate with the projecting pins of the central pinion, stop washers held in changeable relation with respect to the segmental pinions and having means for co-acting with the central pinions pins for reference purposes, a stop for limiting clockwise rotation of the central pinion for setting purposes, and knobs for rotating as a whole 40 the pinions, stop washers and segmental pinions.

LAURENT DESTINAY.
